UNITED STATES PATENT OFFICE

WILLIAM DUBILIER, OF NEW YORK, N. Y., ASSIGNOR TO DUBILIER CONDENSER CORPORATION, OF NEW YORK, N. Y., A CORPORATION OF DELAWARE

CONDENSER

Application filed September 3, 1924. Serial No. 735,566.

This invention relates to electrical condensers; particularly electrical condensers adapted for high frequency and high potential operation, as in radio circuits.

5 An object of this invention is to provide a condenser the type of which is enclosed in a suitable housing which is so constructed that the body of the condenser can be very conveniently mounted in the housing and supported therein in a manner that permits the condenser to be easily put into the housing and secured in operative position or dismounted and taken out when occasion for its removal arises.

10 15 The nature of the invention is set forth in the following description taken with the drawings which show the best form of my invention now known to me, and the novel characteristics of my improvements are defined in 20 the appended claims. While I show only one form in which the invention is embodied, I, of course, reserve the right to make any changes which are consistent with the scope and principle of the invention, as indicated by the 25 general meanings of the terms in which the claims are expressed.

On the drawings,

Figure 1 shows in vertical section a condenser with a housing according to my invention; and

Figure 2 is a bottom plan of the condenser in the housing with the cover which, in practice, will be fitted over the bottom of the housing, removed.

30 35 The same numerals identify the same parts throughout.

The housing is indicated at 1 and is preferably of very strong construction; I usually make this housing of metal cast into shape; 40 and within the housing is the body of the condenser 2. The lower end of the housing 1 is open and is provided with a removable cover 3 which can be removably fastened in place in any suitable way. The other end or 45 top of the housing is also open, but this end too is closed by a cover plate 4 removably held in place by any suitable means such as screws and at the center of this cover plate is an aperture of considerable diameter 5, the edges 50 of which may be rounded as shown. Held

against the inner and outer faces of the cover 4 are tubular insulators 6 which may be made of vitreous material and are associated with caps 7, for example, which may be of metal and are arranged to close the open bottom of the inside or lower insulator 6, and the open top of the outside or upper insulator 6; the lower end of the outside insulator and the upper end of the inside insulator abutting the outer and inner faces respectively of the plate 55 or cover 4, so as to surround and conceal the aperture 5. Both the caps 7 have threaded openings at the middle and through these openings passes a central terminal rod or stem 9 projecting at both ends through the 60 caps 7 and provided at its upper extremity with binding nuts 10 to enable the conductor to be secured thereto. Of course, by turning up the caps 7 on this rod 9, the two caps can be made to press firmly against the opposite 65 extremities of the insulator 6, and the rod 9 will, of course, pass centrally through the aperture 5 so as to be located a material distance from the periphery of this aperture at 70 all points.

75 The rod 9 extends down into the housing a material distance below the inside cap 7 and the body of the condenser 2 is suspended from this rod which serves as a support for the condenser. While the actual type of condenser 80 may be varied, I show the condenser 2 as consisting of a central block 11 having a threaded opening passing through same to receive the lower end of the rod 9, and the condenser comprises two halves, each of which 85 is clamped against one of the opposite side faces of the block 11. The two halves in question are indicated by the numeral 12. They will include, of course, sheets or elements of electrically conductive material separated by 90 a suitable dielectric, and the end of each half remote from the central block 11 will carry plates or members 13 which are engaged by resilient elements 14 that may have the form of leaf springs and be disposed between the 95 members 13, and pressure members 15 at each of the two ends of the condenser, the two members 15 being secured together by wires or cables which encircle the two members 15 of the condenser between them, the wires or ca- 100

bles 16 being under sufficient tension to draw the two plates or members 15 towards each other and make the springs 14 press against the end plates 13 of the condenser, so as to force the two halves 12 against the opposite faces of the head 11, and thus keep the conductive elements and the dielectric in firm engagement over their entire surfaces. The parts 13, 14 and 15 may be of conductive material such as metal, and each of the plates 15 can be connected as by wires or conductors 17 to the body of the housing 1. The housing may have extensions or lugs 18 with openings 19 to enable the housing with the condenser 20 in it to be fastened in position for operation, in connection with the circuit for which it is intended, and the lower end of the rod 9 may be provided with a nut 20 to engage the bottom of the block or head 11.

21 In practice, the conductors 17 will serve as low tension connectors to the low potential sides of the two halves 12 of the condenser; while the high potential sides of the two halves will be joined to the block 11 and terminal rod 9. The conductive elements separated by the insulation of each of the two halves 12 of the condenser may be grouped in any suitable manner, so that the head 11 serves as a high potential terminal with the opposite 25 ends of the two halves constituting the low potential terminals of the condenser joined through the connectors 17 and the body of the housing to the electric circuit. The whole condenser 2 being supported in the housing 1 entirely by means of the rod 9, can easily 30 be mounted and secured on this rod in the housing or taken off this rod and removed from the housing whenever necessary after first removing the lower cover 3. For this 35 purpose, the housing may be made large enough to permit the whole condenser 2 to be turned round therein after the cover 3 is taken off, and the connectors 17 detached, so as to unscrew the condenser from the rod or 40 part 9, or if the housing is smaller, the rod can be turned after taking off the nut 20, so as to unscrew it from the head 11 and the two caps 7 if necessary, until it is disconnected 45 from the condenser.

50 Having described my invention, what I believe to be new and desire to secure and protect by Letters Patent of the United States is:—

1. The combination of a housing, a condenser in the housing, the housing having an opening, a rod detachably secured to the condenser and projecting through the opening and supporting the condenser thereon, hollow insulators surrounding the opening inside and 55 outside of the housing, caps for the insulators, the caps and the rod being threaded for mutual engagement, the condenser having a central block to be mounted on the inner end of said rod, said rod forming one terminal of 60 the condenser, plates, resilient elements, and

pressure members at the ends of the condenser, cables encircling said condenser to exert pressure on said plates, elements and members towards said block, and terminals connecting the condenser to the housing. 70

2. The combination of a housing, a condenser in the housing, the housing having an opening, a rod passing through the opening and supporting the condenser thereon, hollow insulators surrounding the opening inside and 75 outside the housing, and mounting said rod, and clamping means in the casing surrounding said condenser.

3. The combination of a housing, a condenser in the housing, the housing having an opening, a rod supporting the condenser and projecting through the opening, hollow insulators surrounding the opening inside and outside of the housing, caps for the insulators through which the rod passes, and clamping 80 means for the condenser inside the housing. 85

4. The combination of a housing, a condenser within the housing, closure means for the housing, means independent of said housing and closure for clamping the condenser, 90 and a member extending through the housing and serving as a means for supporting the condenser.

5. The combination of a housing, a condenser within the housing, closure means for 95 the housing, means independent of said housing and closure for clamping the condenser, and a supporting member for the condenser extending through the housing, said member serving as a terminal for the condenser. 100

6. The combination of a housing, a condenser within the housing, a closure member for the housing, means independent of said housing and closure for clamping the condenser, a supporting member for the condenser extending through the housing, and means for insulating said supporting member. 105

7. The combination of a housing, a condenser within the housing, a closure member for the housing, means independent of the 110 housing for clamping the condenser, a member serving as the sole supporting means for the condenser, said member extending through the housing and insulated therefrom and comprising one of the terminals for the 115 condenser.

8. The combination of a housing, a closure member for the housing, a condenser within comprising a central head against which the condenser sections are secured, means independent of said housing and closure for clamping said sections to the head, and a supporting member for the condenser engaging said head and extending through the housing, 120 said member comprising the sole supporting 125 means for the condenser.

9. A condenser, a clamp compressing the condenser, and a terminal constituting a sole support for the condenser, said terminal be- 130

- ing disposed so that it is likewise compressed by the clamp.
10. A condenser, a clamp compressing the condenser, and a terminal constituting a support for the condenser, the clamp securing condenser and terminal together, the clamp being disposed so that it compresses the terminal also.
11. The combination of a terminal, a condenser secured to the terminal, and insulation attached to the terminal to enable it to be secured in place and serve as a sole support for the condenser.
12. The combination of a terminal, a condenser, a member clamping the condenser and securing it to the terminal, and insulation attached to the terminal to enable it to be fixed in position and serve as a support for the condenser.
- 20 13. The combination of a terminal, a condenser, a member clamping the condenser and securing it to the terminal, and insulation attached to the terminal to enable it to be fixed in position and serve as a support for the condenser, said member being freely mounted except for its engagement with said condenser.
14. The combination of a casing, a terminal mounted on the casing and a condenser secured to the terminal in the casing, the terminal being the sole support for the condenser in said casing.
- 30 15. The combination of a casing, a terminal mounted on the casing, a condenser mounted upon the terminal, and a member securing the condenser under pressure to the terminal, said terminal being the sole support for said condenser and said member.
- 40 16. The combination of a casing, a terminal mounted on the casing, a condenser mounted upon the terminal, and a member securing the condenser under pressure to the terminal, said terminal being the sole support for said condenser and said member, said member being freely mounted in the casing except for its engagement with the condenser.
- 50 17. The combination of a terminal to be supported in fixed position, a condenser comprising sections affixed to the end of said terminal at different points, and a clamping member securing said sections to said terminal, the clamp being freely mounted except for its engagement with said sections.
- 55 18. The combination of a casing having an opening, an insulating cover for said opening, a terminal mounted upon said cover and extending into the casing, and a condenser attached to the terminal in the casing, the terminal being the sole support for said condenser.
- 60 19. The combination of a casing having an opening, an insulating cover for said opening, a terminal mounted upon said cover and extending into the casing, and a condenser at-
- tached to the terminal in the casing, the terminal being the sole support for said condenser, said condenser comprising sections engaging the terminal at different points.
- 70 20. The combination of a casing having an opening, an insulating cover for the opening, a terminal mounted on the cover and extending into the casing, a condenser in the casing, a clamping member for securing the condenser and terminal together, the terminal being the sole support for said condenser and said member.
- 75 21. The combination of a casing having an opening, an insulating cover for the opening, a terminal mounted on the cover and extending into the casing, a condenser in the casing, and a clamping member for securing the condenser and terminal together, the terminal being the sole support for said condenser and said member, said condenser comprising sections engaging the terminal at different points and being encircled by said member.
- 80 Signed at New York, in the county of New York and State of New York, this 27th day of August A. D. 1924.
- 90 WILLIAM DUBILIER.
